(57) **CLAIM**

The ornamental design for an octopus-shaped food product, as shown and described.

DESCRIPTION

FIG. 1 is a front perspective view of the octopus-shaped food product of the present invention.

FIG. 2 is a top view thereof.

FIG. 3 is a front view thereof.

FIG. 4 is a side view thereof.

FIG. 5 is a bottom view thereof; and,

FIG. 6 is a back view thereof, and is also a front view of a second embodiment of the octopus-shaped food product, the only difference being the omission of the eyes.
